UNITED STATES PATENT OFFICE.

CLAY E. McMILLAN, OF COUNCIL GROVE, KANSAS

SAFETY-SHIELD FOR DISK HARROWS.

No. 902,437.

Specification of Letters Patent.

Patented Oct. 27, 1908.

Application filed January 21, 1908. Serial No. 411,885.

To all whom it may concern:

Be it known that I, CLAY E. McMILLAN, a citizen of the United States, residing at Council Grove, in the county of Morris and State of Kansas, have invented a new and useful Improvement in a Safety-Shield for Disk Harrows, of which the following is a specification.

This invention relates to a shield or fender for disk harrows, and the object of the invention is to provide a fender for the cutting blades which will prevent the driver or the horses being cut or injured by said blades.

The invention consists of the novel features of construction hereinafter described, pointed out in the claim and shown in the accompanying drawings, in which

Figure 1 is an end view of a harrow with my device applied thereto. Fig. 2 is a plan view. Fig. 3 is a detail perspective view of the shield removed from the harrow.

In these drawings A represents a harrow now in use and which as manufactured is not provided with any shield or fender for the cutting disks. This harrow is formed in two sections one upon each side of the seat and each section is provided with a rear frame bar A' and a front bar A². It is also provided with braces A³ connecting the two sections with the tongue, said braces converging toward their front ends. My shield consists of two bars B for each section of the harrow, which bars are angled, the horizontal por-

tions resting transversely across the frame members A' and A² and being bolted to them. A forward portion of each bar B stands downwardly and forwardly and to each pair of bars is secured a flat metal plate C which forms a downwardly and forwardly inclined shield above and in advance of the cutting disks of each section. Each of these shields is slotted obliquely from its lower edge as shown at C' and through these slots pass the braces A³.

By the construction herein shown and described, protection against injury from the blades is provided for without interfering with the handling of the harrow, without increasing the amount of room required for turning it and without adding an excessive weight to any particular part of it.

Having thus fully described my invention, what I claim as new and desire to secure by Letters Patent, is:—

The combination with a sectional disk harrow, having tongue braces, of angled bars arranged in pairs, one pair being carried by each section of the harrow, shields carried by the angled portions of said bars, said shields being provided with oblique slots extending from their lower forward edges, the tongue braces passing through said slots.

CLAY E. McMILLAN.
